HEATING ELEMENT ASSEMBLY

Joseph Woodley, St. Louis, Mo., assignor to
 Knapp-Monarch Company, St. Louis, Mo., a
 corporation of Missouri

Application June 26, 1936, Serial No. 87,459

15 Claims. (Cl. 219—19)

An object of my invention is to provide a heating element assembly for sandwich toasters, waffle irons and the like, which is comparatively inexpensive to manufacture and very simple, yet durable when connected with a plate or the like to be heated.

A further object is to provide a heating element assembly including a terminal member which is connected with the terminal ends of a heating element, and which is so supported that it is rigidly mounted relative to the entire assembly, yet a single tongue and slot connection serves the purpose of holding the parts in assembled position.

Still a further object is to provide a terminal member having a pair of slot and tongue connections with a supporting plate or the like for a heating element, the tongue of one connection being bent for retaining purposes and the tongue of the other connection serving the purpose of preventing rotation of the terminal member relative to the supporting plate after the single tongue has been manipulated by bending for retaining purposes.

Still a further object is to provide a heating element assembly in which a sheet metal plate serves the purpose of supporting insulating elements for the heating element and as a support for a terminal member connected with the terminal ends thereof.

With these and other objects in view, my invention consists in the construction, arrangement and combination of the various parts of the device, whereby the objects contemplated are attained, as hereinafter more fully set forth, pointed out in my claims, and illustrated in the accompanying drawing, in which:

Figure 1 is a plan view of a heating element assembly embodying my invention, the casing associated therewith being shown in section.

Figure 2 is a similar view on a reduced scale omitting the casing and showing a first step in the assembly of the heating element assembly, which comprises the mounting of a supporting plate on the plate to be heated by the heating element.

Figure 3 is a similar view showing the insulating elements in position.

Figure 4 is a similar view showing the heating element and a terminal member being placed in position.

Figure 5 is a sectional view on the line 5—5 of Figure 1.

Figure 6 is a sectional view on the line 6—6 of Figure 5.

Figure 7 is an enlarged sectional view on the line 7—7 of Figure 1.

Figure 8 is an enlarged sectional view on the line 8—8 of Figure 1; and

Figure 9 is a perspective view of a terminal member used in my heating element assembly.

On the accompanying drawing I have used the reference numeral 10 to indicate a plate or the like to be heated. By way of illustration I have shown a sheet metal plate, this plate being the upper plate of a sandwich toaster. A casing 12 may be suitably associated with the plate 10 in the usual manner for enclosing the heating element 14.

For supporting the heating element 14 and spacing it from the plate 10, I provide a supporting plate 16 and insulating elements 18. The plate 16 is provided with a pair of downwardly extending flanges 18a terminating in outwardly extending flanges 20 which may be spot welded or otherwise suitably secured to the plate 10 for support relative thereto. The elements 18 have notches 19 in their outer ends to receive the heating element 14.

The plate 16 may be provided in its periphery with slots 22 receiving the inner ends of insulating elements 18 in the manner shown in Letters Patent No. 2,014,001, of September 10, 1935.

I provide a terminal member A for the terminal ends of the heating element 14, which is formed of sheet metal having a body portion 24, a mounting portion 26 and a pair of tongues 28 and 30. The terminal member 24 is perforated as indicated at 32 through which terminal connectors, such as rivets or the like 34, extend. These are suitably insulated relative to the body portion 24 by making the perforations 32 enlarged relative to the diameter of the rivets 34, as shown in Figure 7, and providing insulating washers 36 under the heads of the rivets. The upper washer 36 is retained against lateral displacement by ears 38 formed on the terminal member A.

The terminal ends of the heating element 14, as indicated at 14a, are electrically connected with the rivets 34 by being positioned under the heads thereof. Clips 40 are also positioned under the heads and are connected with lead wires 42 extending to the terminal prongs or supply cord for the electric appliance. The terminal members A are provided with slots 44, while the supporting plate 16 is provided with a tongue 46 for coaction therewith. The supporting plate 16 is also provided with a slot 48 to receive the tongue 30 of the terminal member A.

In the assembly of my heating element assem-

55

bly, the plates 10 and 16 connected with each other as in Figure 2 is the first step. The insulating elements 18 are then positioned as shown in Figure 3, whereupon the heating element 14 with its ends suitably connected with the terminal member A is wound around the insulating elements (it being stretched during this step of the operation to place it under tension), after which the terminal member A is positioned with its tongue 30 received in the slot 48 and the tongue 46 received in the slot 44 of the terminal member. Thereafter the tongue 46 is twisted as shown in Figures 1, 5 and 8, which retains the portion 26 of the terminal member in contact with the supporting plate 16, and the tongue 30 preventing rotation of the terminal member. In this position the tongue 28 as shown in Figure 5 prevents any accidental bending of the terminal member A toward the plate 10, thus eliminating the possibility of causing a short circuit between the plate and one of the terminal connectors or rivets 34.

It will be obvious that I have provided a very inexpensive heating element assembly, both from the standpoint of required material and required time for assembly. The supporting plate 16 is inexpensively formed in a suitable die which forms the flanges 18 and 20 and a reinforcing bead 50 if desired.

30 The insulating elements 18 are readily positioned and the heating element 14 is readily supported on them whereupon it takes but a minimum of time to perform the single operation of twisting or bending the tongue 46 to retain 35 the terminal member in position. After once assembled, the parts are not apt to become disassociated or sprung to undesirable positions during operation of the appliance.

40 Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

1. In a heating element assembly, a plate to be heated, a supporting plate secured in spaced relation thereto, insulating elements supported by the peripheral edge of said supporting plate, a heating element supported by said insulating elements and a terminal member having the ends of said heating element connected therewith, said terminal member having a pair of slot and tongue connections with said supporting plate, one of said connections having the tongue thereof bent for retaining purposes and the other one entering its slot to prevent rotation of said terminal member relative to said supporting plate.

2. In a heating element assembly, a plate to be heated, a supporting plate secured in spaced relation thereto, insulating elements supported by the peripheral edge of said supporting plate, a heating element supported by said insulating elements and a terminal member having the ends of said heating element connected therewith, said terminal member having a pair of slot and tongue connections with said supporting plate, one of said connections having the tongue thereof bent for retaining purposes and the other one entering its slot to prevent rotation of said terminal member relative to said supporting plate, said terminal member having a projection extending 70 toward said first plate to prevent bending of

said terminal member to a position contacting therewith.

3. In a heating element assembly, a member to be heated, a support mounted thereon and spaced relative thereto, insulating elements mounted on said support, a heating element supported on said insulating elements and a terminal member having the ends of said heating element connected therewith, said terminal member having a slot and tongue connection with said support, the tongue thereof being bent to retain said terminal member in assembled position and a second slot and tongue connection between said support and said terminal member to prevent rotation of said terminal member relative to said support. 15

4. In a heating element assembly, a plate member to be heated, a support mounted thereon and spaced relative thereto, insulating elements mounted on said support, a heating element supported on said insulating elements and a terminal member having the ends of said heating element connected therewith and means for connecting said terminal member to said support, said terminal member having a projection extending toward and engaging said plate member to prevent bending of said terminal member to a position contacting with the plate member. 25

5. In a heating element assembly, a plate, a heating element therefor, a support for said heating element and spaced from said plate, a terminal member connected with the terminal ends of said heating element and means for mounting said terminal member on said support, said terminal member having a projection extending toward and engaging said plate to prevent bending of said terminal member to a position contacting therewith. 30

6. In a heating element assembly, a plate or the like to be heated, a heating element for heating said plate, a supporting plate connected with and spaced from said first plate, said supporting plate having slots in the edge thereof, insulating elements received in said slots, said insulating elements supporting said heating element and a terminal member connected with the terminal ends of said heating element, said terminal member comprising a sheet metal element having perforations, terminal connectors for the terminal ends of said heating element extending through said perforations and insulated relative to said terminal member, said terminal member having a slot, a tongue formed on said supporting plate and extending through said slot, said tongue being bent for retaining said terminal member on said supporting plate and slot and tongue means for preventing rotation of said terminal member relative to said supporting plate. 45

7. A heating element assembly comprising a member to be heated, a sheet metal plate secured in spaced relation thereto, insulating elements supported by said supporting plate, a heating element supported by said insulating elements and a terminal member for the terminal ends of said heating element, said terminal member comprising a strip of sheet metal having a portion for contact with the face of said supporting plate, a projection for contact with said member to be heated when said first portion is in contact with said supporting plate and a slot and tongue connection between said first portion and said supporting plate. 60

8. A heating element assembly comprising a member to be heated, a sheet metal supporting plate secured in spaced relation thereto, insulat- 70

ing elements supported by said supporting plate, a heating element supported by said insulating elements and a terminal member for the terminal ends of said heating element, said terminal 5 member comprising a strip of sheet metal having a portion for contact with the face of said supporting plate, a projection for contact with said member to be heated when said first portion is in contact with said supporting plate, 10 a slot and tongue connection between said first portion and said supporting plate and means of cooperation between said first portion and said supporting plate to prevent rotation of said terminal member on the axis of said slot and tongue 15 connection.

9. In a heating element assembly, a plate to be heated, a sheet metal supporting plate secured in spaced relation thereto, slots in the edge thereof, insulating elements supported in said 20 slots and having notches in the outer ends thereof, a heating element extending through said notches and thereby supported by said insulating elements and a terminal member having the ends of said heating element connected therewith, said terminal 25 member having a pair of slot and tongue connections with said supporting plate, one of said connections having the tongue thereof bent for retaining purposes and the other one entering said slot to prevent rotation of said terminal 30 member relative to said supporting plate.

10. In a heating element assembly, a plate to be heated, a sheet metal supporting plate secured in spaced relation thereto, slots in the edge thereof, insulating elements supported in said 35 slots and having notches in the outer ends thereof, a heating element extending through said notches and thereby supported by said insulating elements and a terminal member having the ends of said heating element connected therewith, said 40 terminal member having a pair of slot and tongue connections with said supporting plate, one of said connections having the tongue thereof bent for retaining purposes and the other one entering said slot to prevent rotation of said terminal 45 member relative to said supporting plate, said terminal member having a projection extending toward said first plate to prevent bending of said terminal member to a position contacting therewith.

11. In a heating element assembly, a member to be heated, a support mounted thereon and spaced relative thereto, insulating elements mounted on said support, a heating element supported on said insulating elements and a terminal 50 member having the ends of said heating element connected therewith, said terminal member having a slot and tongue connection with said supporting member, the tongue thereof being bent to retain the terminal member thereof in position,

said terminal member having a projection extending toward said first member to prevent bending of said terminal member to a position contacting with the first member.

12. In a heating element assembly, a member 5 to be heated, a support mounted thereon and spaced relative thereto, insulating elements mounted on said support, a heating element supported on said insulating elements and a terminal member having the ends of said heating element 10 connected therewith, said terminal member having a slot and tongue connection with said supporting member, the tongue thereof being bent to retain the terminal member in position, said supporting member having a slot and said terminal member having a tongue for coaction therewith to prevent rotation of said terminal member relative to said supporting member, said terminal member having a projection extending toward and engaging said first member to prevent 15 bending of said terminal member to a position contacting with the first member.

13. In a heating element assembly, a heating element, a support therefor, a terminal member connected with the terminal ends of said heating 25 element and means for mounting said terminal member relative to said support comprising a pair of slot and tongue connections, one of said connections having the tongue thereof bent for retaining purposes, the other one entering its slot 30 to prevent rotation of said terminal member relative to said support and both of said slot and tongue connections preventing shifting of said terminal member relative to said support.

14. In a heating element assembly, a heating 35 element, a support therefor, a terminal member connected with the terminal ends of said heating element and means for mounting said terminal member relative to said support comprising a pair of slot and tongue connections, one of said connections having the tongue thereof bent for retaining purposes and the other one entering its slot to prevent rotation of said terminal member relative to said support, said terminal member having a projection extending toward and engaging 40 heating element connected therewith, said terminal member to a position contacting therewith.

15. In a heating element assembly, a supporting element, a heating element supported thereby and a terminal member having the ends of said 50 heating element connected therewith, said terminal member having a pair of slot and tongue connections with said supporting element, one of said connections having the tongue thereof bent for retaining purposes and the other one entering 55 its slot to prevent rotation of said terminal member relative to said supporting plate.

JOSEPH WOODLEY.
